(57) **CLAIM**

I claim the ornamental design for an elevated support grate, as shown.

DESCRIPTION

FIG. 1 is a front perspective view of the elevated support grate according to a first embodiment of the invention;

FIG. 2 is a front elevation view of the elevated support grate according to the first embodiment of the invention;

FIG. 3 is a top view of the elevated support grate according to the first embodiment of the invention;

FIG. 4 is a left side view of the elevated support grate according to the first embodiment of the invention;

FIG. 5 is a right side view of the elevated support grate according to the first embodiment of the invention;

FIG. 6 is a bottom view of the elevated support grate according to the first embodiment of the invention;

FIG. 7 is a rear perspective view of the elevated support grate according to the first embodiment of the invention;

FIG. 8 is a rear elevation view of the elevated support grate according to the first embodiment of the invention;

FIG. 9 is a section view of the elevated support grate according to the first embodiment of the invention;

FIG. 10 is a section view of the elevated support grate according to the first embodiment of the invention;

FIG. 11 is a front perspective view of the elevated support grate according to a second embodiment of the invention;

FIG. 12 is a front elevation view of the elevated support grate according to the second embodiment of the invention;

FIG. 13 is a top view of the elevated support grate according to the second embodiment of the invention;

FIG. 14 is a left side view of the elevated support grate according to the second embodiment of the invention;

FIG. 15 is a right side view of the elevated support grate according to the second embodiment of the invention;

FIG. 16 is a bottom view of the elevated support grate according to the second embodiment of the invention;

FIG. 17 is a rear perspective view of the elevated support grate according to the second embodiment of the invention;

FIG. 18 is a rear elevation view of the elevated support grate according to the second embodiment of the invention;

FIG. 19 is a section view of the elevated support grate according to the second embodiment of the invention; and,

FIG. 20 is a section view of the elevated support grate according to the second embodiment of the invention.
